LIGHTING FIXTURE

William Charles Bornhuetter, Maplewood, N. J.

Application May 20, 1952, Serial No. 288,899

1 Claim. (Cl. 240—73)

1

This invention is an improved lighting fixture, particularly a holder for the bulb of an electric lamp adapted to be attached to a support such as an article of furniture.

It is an object of this improvement to provide a holder of a simple construction, to be securely mounted on the support, adjustable into the desired position to give light when required.

The fixture is clearly described herein and the construction is illustrated in the drawings. But alterations in structural details may be made without deviating from the design in which the invention resides.

On the drawings:

Figure 1 is a view showing the fixture mounted at the head of a couch or bed.

Figure 2 is a front view of a base or mounting member for the fixture.

Figure 3 is a rear view of said member; and Figure 4 is a sectional view of said member.

Part of a bed, such as the head board thereof, is indicated at 1, but the fixture can be mounted on any other convenient support. The fixture comprises a base member 2 with a swivelled piece 3 on one face. This piece carries on a portion 4 cut and bent out at right angles, as shown at 5, a fixed hollow boss 6, to which is affixed one end of the flexible tubular casing 7. At the other end of the casing 7 is a lamp socket 8, in which is a knob switch 9. The socket carries the lamp bulb 10. The boss 4 is open and through it and the casing 7 is passed the cord 11 containing the supply conductors for the lamp 10. At its outer end the cord is attached to a plug 12 having metal prongs 13 for insertion into the outlet plug of a wiring system.

The base is shown as rounded in outline, with a straight bent edge 14, and it is affixed to the support 2 by screws 15 through the edge 14. The member 2 is separated from the support except along said edge 14.

The piece 3 is circular and is pivotally connected to the base 2 by a central rivet 16. The

2

base has a circular groove 17 on its inner face concentric with the rivet, and the piece 3 a matching groove 18. In the groove is a round ring 19 with cut ends as at 20, set out of line and compressed between the base 2 and piece 3 by the rivet to serve as a spring, pressing tightly against both the base 2 and piece 3, so that the piece will be held firmly in all adjusted positions.

When the fixture is mounted the casing 4 is manipulated to bring the lamp to give the light where it is needed. The casing 7 can be bent at will.

Having described my invention what I believe to be new is:

15 A lighting fixture comprising a flat base with a straight edge and bent laterally along said edge to be secured in offset position to a support, said base having a rounded portion separate from said edge, a flexible tubular casing bearing a lamp socket at one end, conductors in said casing leading to said socket, a flat round piece having a part cut and bent out affixed to said casing, said rounded portion of the base and said piece being pivotally connected face to face by a central rivet, 20 the rounded portion of said base and said piece having relatively narrow matching grooves concentric with said rivet, and an elastic circular ring with sprung ends in said groove engaging said piece and said portion of the base to hold the 25 piece in adjusted position on the base.
